[57] CLAIM

The ornamental design for a coat hanger body, as shown and described.

DESCRIPTION

FIG. 1 is a front elevational view of a coat hanger body showing my new design;

FIG. 2 is a front elevational view thereof, in the open position;

FIG. 3 is a rear elevational view thereof;

FIG. 4 is a rear elevational view thereof, in the open position;

FIG. 5 is a right side elevational view thereof, the left side being identical;

FIG. 6 is a top plan view of FIG. 5;

FIG. 7 is a bottom plan view of FIG. 5;

FIG. 8 is a right side elevational view of a second embodiment of the design of FIG. 1, the only difference being the increase in the thickness of the body;

FIG. 9 is a top plan view of FIG. 8;

FIG. 10 is a bottom plan view of FIG. 8;

FIG. 11 is an enlarged rear isometric view of FIG. 1;

FIG. 12 is an enlarged front isometric view of FIG. 1. The broken line showing of the hook or stem in FIGS. 1-5, 8, and 10-12 is for illustrative purposes only.
